Primary Examiner — Lauren R Calve*(74) Attorney, Agent, or Firm* — David L. Stott(57) **CLAIM**

The ornamental design for a knob for a cooking station, as shown and described.

DESCRIPTION

FIG. 1 is an isometric front view of a knob for a cooking station shown in environmental use;

FIG. 2 is an enlarged view of the knob for a cooking station according to broken circle "A" shown in FIG. 1;

FIG. 3 is a front view of the knob;

FIG. 4 is a left-side view of the knob;

FIG. 5 is a right-side view of the knob;

FIG. 6 is a top view of the knob;

FIG. 7 is a bottom view of the knob;

FIG. 8 is an isometric front view of a second embodiment of a knob for a cooking station;

FIG. 9 is a front view of the knob;

FIG. 10 is a left-side view of the knob;

FIG. 11 is a right-side view of the knob;

FIG. 12 is a top view of the knob; and,

FIG. 13 is a bottom view of the knob.

The broken lines in the drawings represent portions of the knob and the cooking station that form no part of the claimed design.

1 Claim, 6 Drawing Sheets(56)
